UNITED STATES PATENT OFFICE.

JOSEPH A. COSTELLO, OF CLEVELAND, OHIO, ASSIGNOR TO THE CLEVELAND BRASS MANUFACTURING COMPANY, OF CLEVELAND, OHIO, A CORPORATION OF OHIO.

FAUCET.

Application filed August 1, 1925. Serial No. 47,407.

To all whom it may concern:

Be it known that I, JOSEPH A. COSTELLO, a citizen of the United States, residing at Cleveland, in the county of Cuyahoga and State of Ohio, have invented a new and useful Faucet, of which the following is a specification.

My invention relates to improvements in faucets and more especially to a faucet adapted for use in connection with an oil-tank-wagon and comprising a casing which has an interior chamber having a downwardly discharging outlet and is provided with an upwardly facing valve-seat around the upper end of said outlet for a valve which is arranged to control communication through said outlet and movable in said chamber from and toward said seat and adapted to be actuated by the arm of a shaft during the rotation of the shaft in the direction required to actuate the valve from its closed position into an open position.

Said shaft is arranged substantially horizontally below said chamber and supported from the casing, and one end portion of the shaft is arranged externally of the casing and embraced by a crank for rotating the shaft, and the crank-embraced portion of the shaft and the shaft-embracing portion of the crank are relatively contoured to establish operative connection between the crank and the shaft and to permit tilting of the crank toward and from the casing without interrupting said operative connection, and one object of my invention is to provide said crank and the casing with simple and highly practical means whereby the crank, when it has been tilted to the required extent toward the casing after the hereinbefore mentioned rotation of the shaft to the required extent, is held against movement in the direction required to permit closing of the valve.

Preferably said means for holding the crank against said movement comprise a member spaced from the shaft-embracing portion of and rigid with the crank and projecting toward the casing and also comprise a shoulder formed on and externally of the casing and facing in the direction of the hereinbefore mentioned rotation of the shaft, and another object is to cause said shoulder to be overlapped by said projecting member of the crank when the crank has been tilted to the required extent toward the

casing after said rotation of the shaft to the extent required.

Another object is not only to provide the casing, at the front and externally, with a hook arranged below the valve-seat for receiving the bail of a bucket used for receiving the discharge from the faucet, but to reinforce the casing, at the inner end of said hook, from said hook to and a suitable distance above said seat.

Said casing is preferably reinforced, at its upper end, by an externally screw-threaded bonnet screwed into and surrounded by the upper end portion of the casing, and another object is to inexpensively but adequately reinforce the casing from said hook to said bonnet-surrounding portion of the casing.

Another object is to facilitate the manufacture and assemblage of the component parts of my improved faucet, and to render the faucet practical and convenient and simple and durable in construction.

With these objects in view, and to attain other objects hereinafter appearing, this invention consists in certain features of construction, and combinations and relative arrangements of parts, hereinafter described in this specification, pointed out in the claims, and illustrated in the accompanying drawings.

In said drawings, Figure 1 is a front elevation of a faucet embodying my invention. Fig. 2 is a view taken along line 2—2 in Fig. 1, looking downwardly. Fig. 3 is a right-hand side elevation in relation to Fig. 1. Fig. 4 is a horizontal section taken along line 4—4 in Fig. 3, looking downwardly. Fig. 5 is a vertical section taken along line 5—5 in Fig. 1, looking leftward. Fig. 6 is a vertical section taken through the casing along line 6—6 in Fig. 3, looking rearwardly, but in Fig. 6 the valve is shown as having been actuated into an open position by the hereinbefore mentioned crank, and said crank is shown tilted toward the casing, whereas in Fig. 3 said crank is shown in the position which it occupies in the closed position of the valve. Fig. 7 is a section taken along line 7—7 in Fig. 6, looking outwardly. Fig. 8 is a section taken along line 8—8 in Fig. 7, looking in the direction indicated by the arrow.

Referring to said drawings, 12 indicates a metal casing which (see Fig. 5) has an interior chamber 13 and comprises an integral spout or tubular member 14 arranged below said chamber and forming the fluid outlet of the chamber. The casing 12 is provided, at the rear of the chamber 13, with a rearwardly projecting internally screw-threaded tubular member 15 which 5 communicates with said chamber and forms the fluid-inlet of the chamber and is adapted to be screwed onto a tank-wagon pipe or other supply-pipe or tubular member (not shown).

10 The casing 12 (see Figs. 5 and 6) is internally provided, at the upper end of the outlet-member 14, with an upwardly facing annular valve-seat 16, and said outlet-member is arranged to communicate, at its upper end, with the chamber 13 in an open position of the valve 17 which is shown closed in Fig. 5 and open in Fig. 6. Said valve is formed in any approved manner and arranged to control communication between 15 said chamber and said outlet-member and to be in fluid-tight engagement with the seat 16 when the valve is closed. Said valve is arranged to move upwardly in the chamber 13 in opening, and obviously said chamber discharges into the outlet member 14 when the valve is open. Said valve comprises a substantially vertically upwardly projecting rigid stem 18 which extends into a chamber 19 formed internally of the central portion 20 of an externally screw-threaded metal bonnet 20 screwed, at the upper end of said chamber, into the upper end portion of and therefore surrounded by and removable from the casing 12. A coiled spring 21 is coiled around the stem 18 and confined between the valve 17 and the upper end wall of the chamber 19 and acts to retain the valve in its closed position.

25 The valve 17 (see Figs. 5 and 6) comprises a substantially vertically downwardly projecting stem 22 arranged internally and centrally of the upper portion of the outlet-member 14 of the casing in the closed position of the valve, and said stem has a lower end face 23 engaged by a forwardly projecting arm 25 of a substantially horizontal shaft 24 shown arranged substantially at a right angle to and rearward of said stem and extending from side to side of and supported from the casing. The upper portion of the outlet-member 14 of the casing has a rearward enlargement 26 which, as shown in Figs. 4 and 5, extends rearwardly and circumferentially of the adjacent portion and endwise of the shaft 24. The shaft-arm 25 extends from within the portion 26 of the casing to and under the valve-stem 22 and (see Fig. 5) consists preferably of a single metal piece embracing the shaft and conforming to external flat surfaces 28 on

the shaft. Said shaft (see Figs. 4 and 6) extends leftward of the shaft-arm 25 and, between its left-hand end and said arm, is cylindrical and has bearing in the casing.

Adjacent the right-hand side of the shaft-arm 25 (see Fig. 4) is a stuffing box 30 formed around the shaft 24 in any approved manner, and said shaft extends through said box and outwardly from the outer end of the box and therefore has its right-hand end portion externally of the casing, as shown in Figs. 3 and 4. The shaft 24 is provided, at the inner end of the stuffing box 30, with a flange 31 which is circular externally, as shown in solid lines in Fig. 4 and in dotted lines in Fig. 3, and spaced from the right-hand side of the arm 25 and abuts against a shoulder 32 formed (see Fig. 4) internally of the portion 26 of the casing between the flange 31 and said arm and facing in the direction of the right-hand end of the shaft and cooperating with said flange in preventing endwise displacement of the shaft in the opposite direction. Between said flange and said arm the shaft is cylindrical and has bearing in said portion 26 of the casing.

The shaft 24 (see Figs. 3, 4, 7 and 8) is adapted to be rotated by a crank 33 shown applied to the right-hand end portion of and operatively connected with the shaft as will hereinafter appear, and said crank terminates, at its inner end, in an externally circular member 34 projecting endwise of the shaft in the direction of the casing 12 and having a hole 35 which is formed centrally of and extends endwise of said projecting member and through the crank so that said projecting member is tubular from end to end and embraces and preferably surrounds said portion of the shaft. Said shaft is cylindrical, as shown in Fig. 4, between its crank-embraced end portion and the flange 31.

The crank-embraced end portion of the shaft 24 (see Figs. 3 and 7) has two substantially parallel external flat surfaces 36 formed at opposite sides respectively of the shaft, and said portion of the shaft also has two substantially corresponding external convex surfaces 37 which extend longitudinally and preferably from end to end of said portion of the shaft, as shown in Figs. 4 and 8, and also extend transversely of the shaft from one to the other of the aforesaid flat surfaces, as shown in Figs. 3 and 7. The convex surfaces 37 therefore curve outwardly longitudinally of the shaft as shown in Figs. 4 and 8, and outwardly transversely of the shaft as shown in Figs. 3 and 7.

The hole 35 in the crank 33 is substantially uniform in dimensions from end to end and is contoured in cross-section as required to conform to the flat surfaces 36 of the crank-embraced portion of the shaft so that

- said hole (see Figs. 3 and 7) has a flat wall 39 next and opposite each external flat surface 36 of the shaft for the purpose of establishing operative connection between the 5 crank and the shaft. Obviously the dimensional uniformity of the hole 35 from end to end and the external convex surfaces 37 of the crank-embraced portion of the shaft render the crank 33 capable of being tilted 10 toward and from the casing 12. It will be observed, therefore, that by the hereinbefore described construction the crank-embraced portion of the shaft and the shaft-embracing portion of the crank are relatively contoured to establish operative connection between the crank and the shaft and to permit tilting of the crank toward and from the casing without interrupting said operative connection.
- 20 The gland 40 of the stuffing-box 30 is provided, at its outer end, with an annular jacket 41 for the projecting member 34 of the crank 33, and said jacket (see Figs. 3, 4, 7 and 8) surrounds said projecting member and is large enough in internal diameter 25 to permit the hereinbefore mentioned tilting of the crank.
- The casing 12 (see Figs. 1, 2 and 3) is externally provided, at the inner side of and 30 opposite the path of the crank 33, with a flange 42 which extends circumferentially of the upper portion of and is concentric in relation to and spaced upwardly from the shaft-embracing portion of the crank and 35 has two recesses 43 and 44 spaced endwise of and formed at the outer longitudinal edge of said flange. Each of said recesses has a rearwardly facing forward wall 45 arranged to form a shoulder which faces in 40 the direction in which the shaft has to be rotated for actuating the valve 17 from its closed position into an open position, and the crank 33 (see Figs. 1, 2, 3, 6 and 7) has an integral member 46 projecting toward the 45 casing 12 and spaced upwardly from the shaft-embracing portion of the crank and arranged to be brought into engagement with the one or the other of said recesses by the required tilting of the crank toward 50 the casing after the rotation of the shaft in said direction to the required extent. When the valve is in its closed position, shown in Fig. 5, the crank 33 is in its extreme forward position, shown in Figs. 1, 2 and 3, and has 55 its projecting member 46 abutting, between the forward extremity of the flange 42 and the forward recess 43, against the outer longitudinal edge or laterally outwardly facing surface 47 of the forward end portion of said flange, as shown in Figs. 1 and 2. It 60 will be observed that said surface 47 faces the path of the crank and extends from the shoulder formed by the wall 45 of the forward recess 43 in a direction opposite to 65 the direction in which the crank is moved in opening the valve and that the projecting member 46 of the crank moves from opposite said surface during actuation of the crank rearwardly to the extent required to bring said projecting member opposite one 70 of the hereinbefore mentioned recesses so as to permit tilting of the crank toward the casing. Figs. 6, 7 and 8 show the crank as having been tilted toward the casing to the extent required to bring its projecting member 75 46 into engagement with the forward recess 43 after actuating the crank rearwardly the required extent in opening the valve, and Fig. 7 shows said projecting member as extending opposite and as abutting against the shoulder-forming wall 45 of said forward recess. Obviously the quantity of oil or liquid flowing through the outlet-member 14 in a given time would be greater were the crank actuated to bring the 80 projecting member 46 of the crank into engagement with the rearward recess 44 than when said projecting member has been brought into engagement, as shown in Figs. 6 and 7, with the forward recess 43. 85
- The casing 12 (see Figs. 1, 3 and 5) is externally provided, at the front thereof, with a hook 48 arranged below the valve-seat 16 and adapted to receive the bail of a bucket (not shown) used for receiving the 90 discharge of oil or liquid from the outlet-member 14. The upper end portion of the casing is internally reinforced by the casing-surrounded portion of the bonnet 20, and the casing is externally provided, at the front 95 thereof above the inner end of the hook 48, with an integral rib 50 extending substantially vertically upwardly from said end of said hook substantially to the bonnet-surrounding portion of the casing so as to avoid 100 mutilation of or injury to the casing by a blow delivered externally of and against the casing, between the bonnet and the hook, by the hereinbefore mentioned bail during 105 violent or careless application of the bucket 110 to the faucet.
- What I claim is:
1. A faucet comprising a casing which has a fluid-receiving chamber having a fluid-outlet, a valve arranged to control communication through said outlet, a shaft supported from the casing and having a portion thereof externally of the casing and also having means for actuating the valve into an open position during the required rotation of the shaft, and a crank embracing said portion of the shaft, the crank-embraced portion of the shaft having two substantially parallel external flat surfaces formed at opposite sides respectively of the shaft and two substantially corresponding external convex surfaces which extend from one to the other of said flat surfaces and are arranged to permit tilting of the crank toward and from the casing, the crank and the casing having 120 125 130

means whereby the crank, when it has been tilted to the extent required toward the casing after the aforesaid rotation of the shaft to the extent required, is held against movement that would permit closing of the valve, and the shaft-embracing portion of the crank being internally contoured as required to permit the aforesaid tilting of the crank and to conform to said flat surfaces.

- 10 2. A faucet comprising a casing which has a fluid-receiving chamber having a fluid-outlet, a valve arranged to control communication through said outlet, a shaft supported from the casing and having means for actuating the valve into an open position during the required rotation of the shaft and also having an end portion thereof externally of the casing, and a crank embracing said portion of the shaft, the 15 crank-embraced portion of the shaft having two substantially parallel external flat sur-

faces formed at opposite sides respectively of and extending endwise of the shaft and two substantially corresponding external surfaces which extend transversely of the 25 shaft from one to the other and endwise of said flat surfaces and curve outwardly longitudinally and transversely of the shaft, the shaft-embracing portion of the crank being internally contoured as required to 30 permit tilting of the crank toward and from the casing and to conform to said flat surfaces, and the crank and the casing having means whereby the crank, when it has been tilted to the required extent toward the 35 casing after the aforesaid rotation of the shaft, is held against movement that would permit closing of the valve.

In testimony whereof, I sign the foregoing specification.

JOSEPH A. COSTELLO.
